UNITED STATES PATENT OFFICE.

THOMAS VARNEY, OF SAN FRANCISCO, CALIFORNIA.

IMPROVED AMALGAMATOR.

Specification forming part of Letters Patent No. 43,535, dated July 12, 1864.

To all whom it may concern:

Be it known that I, THOMAS VARNEY, of the city and county of San Francisco, and State of California, have discovered certain new and useful Improvements in the Mode of Constructing what is known as "Varney's Amalgamator," for which Letters Patent were issued from the Patent Office of the United States to me, bearing date the 16th day of December, A. D. 1862, and numbered 37,185; and I hereby declare that the following is a full, clear, and exact description of the amalgamator with the improvements, reference being had to the accompanying drawings, making a part of this specification, in which—

Figure 1 is mainly a vertical central section view of the amalgamator with the improvements. Fig. 2 is mainly a top view of the frame upon which the pan is supported and the driving-gear. Fig. 3 is substantially a top view of the interior of the pan with the cover removed.

The particulars in which the drawings differ from the views above mentioned will be apparent on comparing the several figures and reading the following description: The body of the amalgamator consists of a pan or tub, A, with a cover, B, through which there is an opening for the introduction of the pulp to be amalgamated, which consists of pulverized ore and water. This pan is supported upon suitable frame-work. (Shown in Fig. 2.) Around the center of the pan, and extending from its bottom (to which it is cast) to some distance above the cover, stands the vertical tube D, the interior of which constitutes an opening vertically quite through the pan, in order that the shaft C may pass through it. On the bottom of the pan, and secured to it by the bolts e, lies the lower muller, a, being a circular iron plate with a round hole d in its center considerably larger than the base of the tube D. This die or muller may be made in sections, if desired. That portion of the hole through this muller not occupied by the tube D is filled with wood, so as to present a plain surface from the tube to the circumference of the muller. The diameter of this muller is somewhat less than that of the interior of the pan by which the space a' is left to be filled with quicksilver. Above the lower muller is the upper one, b, of like general form and size, having about twelve shoes, c, the form and

relative position of which will be understood by supposing a plate of the diameter and thickness of the lower muller attached to the under side of the upper muller, and sawed into about twelve equal parts by a saw an inch thick, and running in a line drawn from the circumference of the plate to the outside of the tube D, the saw being kept inclined laterally at an angle of forty-five degrees, thus forming radial grooves from the inner to the outer opening. Each shoe is fastened to the muller by a wrought-iron rivet with a head in the form of the frustum of a cone cast into the middle of the shoe and riveted on the upper side of the muller, as shown at f, Fig. 1. At g is shown the old method. The riveting must be into a countersink, so as to leave the upper surface of the upper muller a smooth one. The boss and recess j keep the die in its place. In the lower muller are radial slots similar to those between the shoes of the upper muller. These slots may be inclined laterally or not; but if inclined the inclination should be in a direction opposite to that of the slots between the shoes. These slots (in the lower muller) are filled with wood or some other substance softer than the die, in order that the same may be kept worn slightly in advance of the wear of the die, thus furnishing a wedging entrance for the pulp between the grinding-surfaces, whereby the grinding capacity of the machine is greatly increased.

Over and around the tube D, but not in contact with it, is placed the larger tube E with its base in line with the lower face of the upper muller, and having around its lower end the flange V, upon which rests loosely the ring h, which is cast with and forms a part of the upper muller, and is connected with it by six curved arms or spokes, i, two opposite pairs of which are much nearer together than the others, and the space between each of which pairs is filled by a projection from the periphery of the flange V for the purpose of carrying with it the upper muller when the flange revolves. To the shaft C is fastened the large tube E by the feather k and set-screw l in the hub G. The shaft C passes through its guide-box m, with Babbitt metal n, into and through the hub F of the driving-wheel, in which is a feather sliding vertically in the shaft. This shaft is stepped by the ordinary method into the vertically-sliding box H, which is itself

held in the laterally-adjustable box *o*. The step box rests upon a lighter bar, one end of which is supported by the screw-bolt *w*, Fig. 2, and the other is held by the bolt and hand-wheel, *X*, Fig. 2, by which it may be raised or lowered, raising and lowering with it the shaft, the large tube, and the upper muller. Within the body of the pan there are suspended three curved plates, *r*, Fig. 3, extending from near the upper surface of the upper muller upward and extending in length from the inner side of the pan around to a point near the outside of the large tube, opposite to that from which they start. The lower edges of the curved plates are bent inward, as shown at *s*, Fig. 1, forming the flanges *s*, Fig. 3. The inner ends of the curved plates are secured rigidly to the ring *q*, sufficient in diameter to surround and clear the large tube *E*, the whole being suspended by a rod attached to each curved plate and running up through the cover and hand-wheel *J*, by which the same may be adjusted vertically. The outer ends of the curved plates slide vertically and closely in grooves in the cuneiform projecting *t*, cast upon the inner side of the pan.

The operation is as follows: The space *a'* about the periphery of the lower muller is filled with quicksilver and the pan nearly filled pulp, and the shaft *C* is made to turn at a proper speed (about seventy-five revolutions per minute) by the gearing represented by Fig. 2, or other machinery by which the upper muller is rotated. The pulp between the mullers, by reason of the centrifugal force, is made to pass outward through the radial channels between the dies, and also between the grinding-surfaces of the dies and the lower muller, against, into, and over the quicksilver, thereby causing amalgamation to take place. This outward motion of the pulp keeps the quicksilver entirely away from the grinding surfaces, thereby obviating what has heretofore proved a very serious difficulty, the grinding of the quicksilver. The rotation of the upper muller causes the pulp in the pan to revolve with it. This current is met by the cuneiform projections and the curved plates, and turned inward toward the central openings in the upper muller. The radial slots between the shoes, running from the center opening to the outward one, allow streams of pulp of considerable size to pass with great velocity. The pulp filling these

slots being thus thrown outward tends to leave vacuums in the slots, by which the pulp in the body of the pan is pressed downward with a force equal to that with which the pulp between the mullers is thrown outward, thus causing a rapid and abundant flow of pulp constantly down at the center, out between the mullers against the quicksilver, upward along the inner surface of the pan, against the curved plates, and again to the center, and so round and round till complete pulverization of the quartz and complete amalgamation of the metals take place. By the peculiar form and position of the flanges on the curved plates, they glide under the pulp in advance of the plates, and neutralize the effect of the pressure of the pulp and its tendency to go under the plates, turning it upward, and thereby lessening the amount which escapes beneath the plates, and more effectually drawing the pulp to the center.

In starting the machine after a stoppage these scrapers easily and effectually plow up and remove the compact sediment which forms on the upper muller.

Having thus described my invention, what I claim as new, and desire to secure by Letters Patent, is—

1. The method of fastening the shoes to the upper muller by casting the rivets into the shoes, as shown.
2. The use of the flanges on the lower edges of the curved plates, in the manner and for the purposes set forth.
3. The employment of the space for the quicksilver about the periphery of the mullers with no openings therefrom in the lower muller by which the quicksilver is prevented from being ground, and at the same time is so situated that it is brought into constant and effective contact with the pulp.
4. The use of the slots in the lower muller, filled with wood or its equivalent, for the purposes set forth.
5. The mode of suspending and driving the upper muller by the arms *i* and ring *h* and flange *V* with its projections.

Dated at the city and county of San Francisco, and State of California, this 26th day of April, A. D. 1864.

THOMAS VARNEY.
